BASCUM O. AUSTIN, OF EAST PITTSBURGH, PENNSYLVANIA, ASSIGNOR TO WESTINGHOUSE ELECTRIC & MANUFACTURING COMPANY, A CORPORATION OF PENNSYLVANIA

CONTROL APPARATUS

Application filed April 12, 1926. Serial No. 101,568.

My invention relates to control apparatus and more particularly to arc-rupturing devices of the type generally used for breaking circuits of high amperage.

The object of the invention, generally stated, is the provision of an arc-rupturing device that shall be simple and efficient in operation and readily and economically manufactured.

10 A more specific object of the invention is to provide for the establishment of concentrated local magnetic fields in arc-rupturing devices, to control the travel of arcs during the disrupting process.

15 A further object of the invention is to provide for the utilization of the current that flows in arc horns to build up local concentrated magnetic fields to restrict the travel of arcs.

20 It is also an object of this invention to provide, for the concentration and utilization of the magnetic force built up during the disrupting process, to oppose the tendency of the main arc-rupturing field to reverse the 70 direction of travel of an arc, when it reaches the end of the arc horn.

Other objects of the invention will in part be obvious and in part appear hereinafter.

The invention accordingly, is disclosed in 30 the embodiment thereof shown in the accompanying drawing and comprises the features of construction, combination of elements, and arrangement of parts which will be exemplified in the construction hereinafter set forth and the scope of the application of 75 which will be indicated in the claims.

For a more complete understanding of the nature and objects of the invention reference should be had to the following detailed 40 description taken in connection with the accompanying drawing, in which

Fig. 1 is a view in side elevation of an arc-rupturing device with parts removed to show one embodiment of a device constructed 45 in accordance with this invention,

Fig. 2 is a perspective view of a modification of the invention showing features of the construction,

50 Fig. 3 is a view in section taken along the line III-III of Fig. 2 and,

Fig. 4 is a view in section of the preferred form of the device taken along the line IV-IV Fig. 1.

Referring now to the drawing, the illustrated arc-rupturing device is of a well-known type and comprises a frame-work 1 on which is mounted a stationary contact member 2 and a movable contact member 3, the latter being disposed on a plunger 4 of an air engine 5 which may be any well-known type used for operating such devices. In this particular construction, arc horns 6 and 7 are associated with the contact members 2 and 3, respectively. As shown, the arc horns are disposed to receive arcs that may be drawn between the contact members.

Since the contact member 3 is movable, the arc horn 7 is also mounted to move with the plunger 4 of the air engine 5. Accordingly, the contact member 3 and arc horn 7 are set in fixed relation so that an arc will not be obstructed in travelling from the contact member to the arc horn by a variable and wide air gap.

As is usual practice in arc-rupturing devices of this type, an electromagnet 8 is provided for developing a main arc-rupturing field to cause arcs drawn between the contact members 2 and 3 to travel outward onto the arc horns 6 and 7 and finally disrupt them. The electromagnet may be of any suitable type and in this case, as shown in the drawing, it comprises a core 9 encircled by the lead-in conductor 10.

Ordinarily, during the operation of an arc-rupturing device of this type, when an arc reaches the ends of the arc horns the magnetic field which has been developed by the electromagnet 8 tends to reverse the direction of travel of the ends of the arc and to force them backward along the outer faces of the arc horns. This is particularly true in the case of the lower arc horns and the continual flashing of the arcs into the operating mechanism greatly reduces the life of the arc-rupturing device.

In order to protect the operating mechanism of the arc-rupturing device from the destructive action of the arcs, means capable of building up concentrated local magnetic

fields may be associated with either the upper or lower arc horn. In this particular construction, the means for providing a concentrated local field is shown associated with the lower arc horn, but it will be readily understood that such a device may be provided in conjunction with the upper arc horn.

As shown in Fig. 1, the lower arc horn has mounted thereon, a magnetizable member 11, which in this embodiment of the invention is a plate counter-sunk in the top face of the arc horn. In order to substantially complete the magnetic circuit, pole-pieces 13 are disposed on opposite sides of the magnetizable member 11.

As will be readily understood, these pole pieces may be supported in any suitable manner such as by mounting them on the side walls of the arc chute 14. While only one pole piece may be observed in the drawing, it will be readily understood that a second one is disposed on the opposite wall of the arc chute. Further, the pole pieces are preferably made large enough to permit a considerable movement of the plate 11 with the arc horn 7 without moving it out of cooperative relation with them.

In operation, when an arc has been delivered to the arc horns 6 and 7, the main magnetic arc-rupturing field developed by the electromagnet 8 tends to cause the arc to move outward and to increase its length until it breaks. When the end of an arc reaches the end of the lower arc horn 7, it tends under the influence of the main magnetic field to travel along the outer or lower face of the arc horn toward the operating mechanism of the arc-rupturing device.

The current travelling in the arc horn 7 will induce in the plate 11 and the pole pieces 13 a magnetic flux which builds up a concentrated magnetic field, located adjacent to the lower side of the arc horn and which will flow in a direction opposite to that of the main magnetic field. Consequently, when the end of the arc reaches this local field, its travel inward toward the operating mechanism is stopped and it leaves the arc horn.

Since the plate 11, as it moves with the arc horn 7, is always located between the pole pieces 13, a local magnetic field which will oppose the travel of an arc inward along the lower face of the horn is built up as soon as the arc has travelled far enough outward along the horn to cause a current to flow through the section of the horn extending between the pole pieces. In this manner the desired local magnetic field is established before the arc reaches the end of the arc horn.

In Fig. 2 a modified type of arc horn is illustrated. In this particular construction, the arc horn 15 simulates a plate which has been folded to form two substantially parallel curved arms 16 and 17. In order to pro-

vide the local magnetic field, a U-shaped magnetizable member 18 is mounted upon the lower arm 16 of the arc horn. The member 18 may be retained in position in any suitable manner such, for example, as by riveting plates 19 to the inner faces of the U-shaped member that extends below the arm 16.

When a U-shaped magnetizable member, such as shown in Fig. 2, is provided, there is no need of pole pieces since the desired local magnetic field flows between the arms extending below the member 16. When arc horns of this type are used, they function in the same manner as the arc horn illustrated in Fig. 1 and build up a local magnetic field below the arc horn to restrict the travel of the end of the arc.

Since various changes in the above described construction and arrangement of parts and different embodiments of the invention may be made without departing from the scope thereof, it is intended that all matter contained in the above description or shown in the accompanying drawings, shall be interpreted as illustrated, and not in a limited sense.

I claim as my invention:

1. In an arc-rupturing device, in combination, an arc horn, and means comprising magnetic material for concentrating lines of magnetic force to provide a local magnetic field on the outside of the arc horn to restrict the travel of the end of an arc rearwardly on the arc horn.

2. An arc-rupturing device comprising, in combination, a plurality of contact members disposed for relative movement, electromagnetic means for developing a magnetic field cooperative to rupture an arc drawn between the contact members, a magnetic conductor carried by one of the contact members, and pole pieces disposed adjacent to said magnetic conductor to concentrate lines of magnetic force induced by current flowing in the arc horn to build up a local magnetic field to restrict the travel of an arc rearwardly on the arc horn.

3. An arc-rupturing device comprising, in combination, a plurality of contact members disposed for relative movement, mechanism for operating the arc horns, arc horns disposed to receive an arc from said contact members, one of said arc horns being movable, means for providing an arc-rupturing field capable of forcing an arc outward along the arc horns, pole pieces disposed on opposite sides of the movable arc horn, and a magnetizable member carried by the movable arc horn and disposed to move between said pole pieces, said magnetizable member and pole pieces being adapted to establish a concentrated magnetic field adjacent the outer side of the arc horn, thereby to restrict the travel

of an arc along the outer face of the arc horn toward the operating mechanism.

4. In an arc-rupturing device, in combination, an arc horn for receiving an arc, and a member of magnetic material carried by the arc horn for concentrating lines of magnetic flux to provide a local magnetic field, said member being disposed on the arc horn to locate the local magnetic field in a position to prevent the travel of an arc rearwardly on the arc horn.

5. An arc-rupturing device comprising, in combination, an arc horn for receiving an arc, and means carried by the arc horn for concentrating lines of magnetic flux to provide a local magnetic field, said flux concentrating means being disposed to locate the local magnetic field on the outer side of the arc horn to prevent the travel of the arc rearwardly on the arc horn.

6. In an arc-rupturing device, in combination, an arc horn for receiving an arc, and a U-shaped member of magnetic material carried by the arc horns, the legs of said U-shaped member extending beyond the arc horn to concentrate lines of magnetic flux to provide a local magnetic field adjacent the outer side of the arc horn to prevent the travel of an arc rearwardly on the outer face of the arc horn.

In testimony whereof, I have hereunto subscribed my name this 10th day of April, 1926.
